UNITED STATES PATENT OFFICE.

CASPER VAN HOESEN, OF NEW YORK, N. Y.

ASH AND GARBAGE CAN.

No. 824,891.

Specification of Letters Patent.

Patented July 3, 1906.

Application filed June 16, 1905. Serial No. 265,545.

To all whom it may concern:

Be it known that I, CASPER VAN HOESEN, a citizen of the United States of America, residing at New York city, in the county and 5 State of New York, have invented certain new and useful Improvements in Ash and Garbage Cans, of which the following is a specification, accompanied by drawings of same.

10 This invention embodies improvements in that type of receptacles designed particularly for holding ashes, garbage, or the like, the object of the invention being to secure a construction of receptacle having a maximum degree of durability and one which may be more readily and easily handled than those at present commonly in use.

15 The invention further aims to secure a receptacle which is comparatively light in view of the peculiar construction above mentioned, this being an important feature of the invention.

20 For a full description of the invention and the merits thereof and also to acquire a 25 knowledge of the details of construction of the means for effecting the result reference is to be had to the following description and accompanying drawings, in which—

25 Figure 1 is a broken perspective view of 30 the lower portion of a receptacle embodying the invention. Fig. 2 is a view being of a different portion of the receptacle. Fig. 3 is a broken vertical section of the upper portion of a side of the receptacle. Fig. 4 is a partial 35 horizontal section. Fig. 5 is a side elevation, partially in section, of the complete receptacle. Fig. 6 is a broken detail section taken at the central portion of a side of the receptacle.

40 Corresponding and like parts are referred to in the following description and indicated in all the views of the drawings by the same reference characters.

45 In carrying out the invention the receptacle embodying the same consists of a sheet-metal body or can 1, having the bottom 2, the latter being formed with a pendent flange 3, which abuts with the lower end portion of the can interior of the sides thereof. The upper and lower ends of the can or body of the 50 receptacle are reinforced in a peculiar manner, and the body itself is protected by special parts, the arrangement and construction of which will now be pointed out clearly. At 55 the lower end of the can 1 is located a ring 4,

formed with a lateral flange 5, which projects outwardly from the lower edge portion thereof. The body of the ring 4 is in contact with the inner side of the pendent flange 3 of the bottom 2 of the can, while the flange 5 projects from the ring in such a manner as to abut with the lower end portions of slats 6, arranged exterior of the can 1 in spaced relation to one another. The slats 6 are disposed vertically and are bowed or curved 60 outwardly between the ends thereof, so that the bodies of the slats are virtually spaced from the body of the can 1. The lower extremities of the slats 6, which are adapted to spring in and out when brought into contact 65 with an object, are attached to the body of the receptacle by means of fastenings 7 in the form of bolts, rivets, or the like, said fastenings passing through the ring 4, the flange 3 of the bottom 2, the lower end of the body of 70 the can 1, the lower ends of the slats 6, and also through an exterior ring 8 at the lower end of the receptacle in spaced relation to the sides thereof. The ring 8 surrounds the lower ends of the slats 6, and its lower edge 75 rests upon the top of the flange 5. The fastenings 7 are diagonally disposed, or, in other words, said fastenings incline downwardly toward the inner extremities thereof, passing through the ring 4 near its lower edge, so as to 80 exert a downward tension on the parts, conserving greatly the compactness of the arrangement and the firmness of the connection 85 thereof. The lower extremities of the slats are spaced apart not only by reason of the 90 manner of attaching them to the receptacle-body, but by means of the provision of filling-blocks 9 of segmental form if the receptacle is of cylindrical construction, said filling-blocks 9 being located between the ring 8 95 and the lower end portion of the sides of the can 1 or between the ring 8 and the ring 4, which are arranged concentric of one another, as will be evident. Suitable fastenings 10, formed similarly to the fastenings 7, 100 pass through the blocks 9, attaching the same to the same parts as are secured to the lower ends of the slats 6. The upper end of the can 1 is reinforced by means of a ring 11, similar to the ring 4, but having a flange 12 105 projecting outwardly from its upper edge portion so as to overlap the upper extremities of the slats 6. The ring 11 is arranged interior of the receptacle, and fastenings 13 attach said ring thereto. The fastenings 13 110

2
pass through the ring 11, the slats 6, and clips 14, embracing the upper extremities of the slats, as clearly shown.

The several slats 6 are supported in relative positions not only by the fastening means before described, but by means of a flexible band 15, preferably of metal, which is attached to the several slats at points between the ends thereof, flexibly connecting the same in such a way as to permit free spring movement thereof necessary for obvious reasons. In addition to the band 15 it is designed to utilize a plurality of links 16 to connect the several slats with one another, said links 16 being of course spaced from the outside of the can 1 and effectively preventing spreading of the slats. The link members 16 being loosely connected with the parts 6 may be readily grasped in order to handle the receptacle for emptying purposes or for purposes of transporting the same from one place to another. The links 16 as handles are very convenient for the purpose above mentioned.

25 It is obvious that the lower end of the receptacle is strengthened in such a way as to resist the greatest amount of wear and hard usage, and this feature is very important when the purposes for which the receptacle 30 may be employed are considered. Simplicity of construction of the article will also be evident.

Having thus described the invention, what is claimed as new is—

35 1. In combination, a can, a plurality of

outwardly-curved spring-slats applied to the sides of the can exterior thereof, and flexible means connecting the curved portions of the slats.

2. In combination, a can, a plurality of 40 outwardly-curved slats applied to the sides of the can exterior thereof, and link members loosely connecting the slats.

3. In combination, a can, a plurality of 45 outwardly-curved slats applied to the sides of the can exterior thereof, and a flexible band connecting said slats.

4. In combination, a can, a plurality of 50 outwardly-curved slats applied to the sides of the can exterior thereof, a flexible band 55 connecting said slats, and links loosely connecting the slats to prevent spreading movement thereof.

5. In combination, a can, a plurality of 55 outwardly-curved slats applied to the sides of the can exterior thereof, a flexible band connecting said staves, and links loosely connecting the staves to prevent spreading movement thereof, the links being arranged in spaced relation to the body of the receptacle whereby they may be used as handles 60 for manipulating the same.

In testimony whereof I, CASPER VAN HOESEN, have signed my name to this specification, in the presence of two subscribing witnesses, 65 this 15th day of June, 1905.

CASPER VAN HOESEN.
